ELECTROMECHANICAL INTERLOCK FOR
ELEVATOR DOORSEmory W. Fenn, Chicago, Ill., assignor to Fire-
craft Corporation, a corporation of Illinois

Application May 13, 1943, Serial No. 486,765

16 Claims. (Cl. 187—31)

1

This invention relates to electro-mechanical interlocks for hoistway doors for freight elevators and the like.

It is an object of my invention to provide an electro-mechanical interlock which is substantially tamper-proof.

It is a further object of my invention to provide in connection with biparting door panels an interlock which cannot be rendered inoperative unless the door suspension mechanism also is rendered inoperative.

Another object is to provide a novel, simple, compact electro-mechanical interlock mechanism.

An additional object is to provide an interlock requiring the doors at all floors to be latched before the car can be started; positively preventing opening movement of all latches while the car is in motion or is not at any floor; and positively preventing opening movement of all latches except that associated with the floor at which the car is at rest.

It is also an object of my invention to provide in an automatic or push-button controlled elevator an electro-mechanical interlock having the features noted above, and, in addition, whereby the car-controlling circuit is locked open when the car comes to rest at the selected floor and until a button is pushed, and may then be closed only if all doors are latched.

Further objects and advantages of the invention will appear as the description proceeds.

My invention will be better understood upon reference to the following description and the accompanying drawings, wherein:

Fig. 1 is a fragmentary elevational view of the inner face of a hoistway door and associated operating and interlock mechanism according to my invention, a vertically sliding biparting door being employed for illustrative purposes.

Fig. 2 is an elevational view taken as indicated by the line 2—2 in Fig. 1, the cover for a part of the interlock mechanism being omitted.

Fig. 3 is an enlarged fragmentary elevational view taken as indicated by the line 3—3 in Fig. 2 and showing details of an interlock mechanism for a push-button controlled type elevator in accordance with one form of my invention.

Fig. 4 is a fragmentary elevational view taken as indicated by the line 4—4 in Fig. 3.

Fig. 5 is a view similar to Fig. 3 but with the interlock switch automatically opened.

Fig. 6 is a fragmentary elevational view taken as indicated by the line 6—6 in Fig. 5.

Fig. 7 is similar to Fig. 3 but shows the door latch in open position, the doors controlled by such latch being separated.

Figs. 8 and 9 are fragmentary plan sectional views taken as indicated by the lines 8—8 and 9—9, respectively, in Fig. 7.

2

Fig. 10 is a fragmentary elevational view similar to Fig. 7 but with the automatic switch-opening means omitted, as in the case of a non-automatic elevator.

Referring now more particularly to the drawings, I have shown an elevator well or shaft 20 (Fig. 9) defined by a wall 22 having a door opening of which the sill is shown at 24, a biparting door 26 comprising upper and lower door panels or sections 28 and 30, and a car 32. Attached to the wall 22 at each side is a vertical guide member 34 to which are attached upper and lower vertical guide members 36 and 37 providing guideways 38 in which run guide angles 39 carried at the vertical edges of the door panels and forked guide shoes 40 attached as at 42 near the top and bottom of each angle 39. The forks (Fig. 9) receive and move vertically relative to the respective guide members 36 and 37, shown in other figures.

Secured to the lower door section 30 as at 48 is an arm 50 extending beyond said section and carrying adjacent its free end a bracket 52 through which the lower threaded end 54 of an anchoring member 56 extends, said end 54 receiving a nut 58 by means of which said anchoring member may be retained and adjusted in relation to the bracket member 52. Secured as at 60 to the upper part 62 of the anchoring member 56 is a chain rod 64 whose upper end is attached as at 66 to a flexible suspension member such as a cable chain 68 passing about a wheel or sheave 70 suitably mounted as at 72 in fixed relation to the guide members 34 and 36. The chain depends from the other side of the sheave and is secured as at 74 to the lower part of the upper door section 28. The adjustment of the doors for proper operation of the interlock may be modified by adjustment of the nut 58. Only the flexible portion 68 is in contact with the sheave 70 for all positions of the door sections 28 and 30.

When the door is closed, the sections 28 and 30 are disposed adjacent each other substantially as shown in Fig. 1, rubber or like bumpers 76 carried by either section being provided at suitable intervals between the bottom flange 78 of the upper section and the top flange 80 of the lower door section 30.

The doors may be latched together by any suitable mechanism, of which an illustrative form is shown in Fig. 1. Here, preferably in a suitable frame 82 secured to the inner face of the upper door section 28, there is pivotally attached as at 84 a bell crank lever 86 having a handle 88 (on the outside as well as the inside in the case of a push-button elevator) conveniently accessible to the operator on a car at rest at the associated floor level, and a second arm 90 extending in a generally vertical direction where it is resiliently maintained preferably as by a compression spring

§2 disposed between an adjustable abutment 94 and a lug 96 formed on the lever 86. The arm 90 is formed at its lower end with a hook or catch 98 adapted to extend through an opening 100 in the top 80 of the lower section 30 and adapted also, when projected through said opening 100, to be moved by the spring 92 under and beyond the wall of the opening 100 as shown in Fig. 1, so as to latch the door sections together.

Pivotedly connected as at 102 to the lever arm 10 90 is an interlock latch bar 104 slidably guided in a block 106 suitably attached as to the angle 39 of the door section 28. The latch bar 104 is adapted to extend beyond the angle 39 and has an offset lug 108 adapted to cooperate with interlock mechanism in a housing 110 having a removable cover 112 and mounted as by suitable bolts, one of which is shown at 114, on the stationary guide members 34 and 36.

In accordance with my invention, there is provided in association with each landing a switch lever arm 118 pivoted in the housing at 120. A locking bolt 122 may be connected to the lever 118 in any suitable manner, and for example may have a slotted upstanding boss 124 pivotally connected as at 126 to a yoke or fork 128 on the lever 118. The housing 110 preferably has a guide opening 130 for sliding movement of a projection 132 extending from the bolt 122. The bolt 122 at the end 134 thereof opposite the projection 132 is adapted to slidably bear on the bearing surface 136 of the housing 110, the only other sliding contact between the bolt and the housing occurring between the bottom of the opening 130 and the bottom of the bolt extension 132, whereby friction is at a minimum. Said end 134 of the bolt 122 has a notch 138 open and flared at the top as at 140 to facilitate entry of the lug 108 on the latch bar 104 into the notch.

The lever 118 is provided with an insulating plate or block 142 from which projects a pin 144 about which a coil spring 146 is disposed, said pin having a non-circular portion passing through a metallic bridge member 148 and formed at its free end to retain the bridge in association therewith, the spring 146 constantly urging the bridge 148 toward the free end of the pin. The bridge 148 may be provided with electric contact points 150 and 152, adapted to engage respectively stationary contacts 154 and 156 mounted on an insulating block 158 fixed to the housing 110. The contacts 154 and 156 are in an electric circuit from which wiring 160, suitably insulated, extends through the housing 110 to a relay 162 controlling the elevator car control motor 164 connected to the electric line. The bridge 148 with its contacts 150 and 152 and the points 154 and 156 constitute a switch 166 which, with the switch 168 in series with the source of supply 167 and controlled directly by the operator, as by push-button, in an automatic elevator, or otherwise in a non-automatic elevator, controls the operation of the motor relay and hence the motor.

Mounted in suitable bearings in the housing 110 is a rock shaft 170 having an outward extension to which is adjustably secured an arm 172 carrying a cam roller 174 adapted to cooperate with a stationary cam 176 on the car if the car is not push-button controlled or with a retiring cam (not shown) with which the car, if push-button controlled, is equipped. Referring now more particularly to the latter type of car, it is well known that pushing any button closes a switch 168 and this operates a solenoid to retire the retiring cam, and if the car is put into mo-

tion the cam will remain in a retired position. When the car nears the selected floor, the retiring cam will be automatically projected to a position at which it operates to engage the roller 174 and swing the arm 172 to a more nearly vertical position, thereby opening the switch 166 at the proper time to insure the car's coming to rest with its floor at the level of the sill 24. The use to which I put the retiring cam will appear presently.

Fixed for rotation with the rock shaft 170 within the housing 110 is a locking arm 178 urged by a spring 180 in a direction to position the end 182 of the locking arm behind a locking lug 184 on the switch arm 118 (Fig. 4), so as to obstruct movement of the switch arm toward the left as shown in the drawings, i. e., toward open-switch position and prevent unlatching of the door, the locking arm 178 however being movable by the action of the retiring or other cam on the roller 174 against the resistance of said spring, to a position (Fig. 6) permitting open-switch movement of the switch arm 118.

Also mounted for rotation with the rock shaft 170 is a safety arm 186 which may be employed in connection with a push-button controlled car, said arm 186 carrying a cam 188 of insulation material movable, by the action of the retiring cam, between the contact bridge 148 and the adjacent stationary contact 154 to lock said bridge in open-switch position, said safety arm being urged by the spring 180 toward inoperative position (Fig. 3), which it occupies upon retirement of the retiring cam.

The housing 110 has an opening 190 permitting the bolt 122 to be projected partially out of the housing, the housing being provided with a suitable stop 192 engageable with the lever 118, or other suitable means being provided, to limit the extent to which the bolt 122 may be projected from the housing toward the door.

When the door is open, i. e., when the door panels 28 and 30 are substantially apart, the latch bar 104 is entirely outside of the housing 110 as may be gathered from Fig. 7, an adjustable stop 194 (Fig. 1) being provided to limit the extent to which the latch bar 104 may be projected by the latch spring 92.

When the door sections are latched together and the car has started on its trip, the parts are disposed as shown in Figs. 1 to 4, wherein, referring particularly to Fig. 3, it will be noted that the switch 166 is closed, the safety switch-opening cam 188 is in inoperative position, and the end 182 of the locking arm 178 is disposed in obstructing relation to the lug 184 on the lever 118, as shown in Fig. 4, making it impossible for the latch bar 104 to be retracted. Thus it is impossible to accidentally open the switch 166 when the car is in motion and until the retiring cam on the car operates on the roller 174. When the retiring cam thrusts the roller 174 aside (to the right in Fig. 2), the rock shaft 170 and with it the locking arm 178 and the safety arm 186 are rotated against the resistance of the spring 180. This rotation of the arm 186 causes its cam 188 to engage the adjacent projecting portion of the contact bridge 148, forcing said bridge against the resistance of the spring 146 to the position shown in Fig. 5, thereby separating the contact 150 from the contact 154 so as to open the switch 166, bringing the car 32 to a stop with its floor flush with the sill 24. This rotation of the locking arm 178 causes the end 182 of said arm to be shifted to a

position out of obstructing relation to the lug 184 of the lever arm 118, as shown in Fig. 6.

Now the operator raises the handle 88 (Fig. 1), pulling the latch bar 104 to the left from its Fig. 5 position, the lug 184 moving past the locking arm end 182 to the extent permitted by the housing 110, as at 192, until the interlock mechanism is arranged substantially as shown in Fig. 7 (in which however the latch bar 104 is shown somewhat elevated, for a purpose which will appear). In this arrangement the contact 152 has separated from the contact 156. Raising the handle 88 also moves the hook 98 laterally sufficiently to enable it to pass out of the opening 100 of the lower door panel 30 as the door panels 28 and 30 are separated. As the door panels are separated, the latch bar 104 passes upwardly out of the notch or socket 130 and clear of the housing 110. It will be noted that when the locking bolt 122 is withdrawn by the latch bar 104 as just described, the projection 132 on said bolt is shifted to a position enabling the upper end 62 of the anchoring member 56 to pass down clear of such projection, as is evident from Fig. 7, so that the further upward and downward movements of the respective door panels 28 and 30 are unobstructed. The chain rod 64 is guided by a guide element 196 suitably attached as at 198 to the housing 110.

The adjustable stop 194 (Fig. 1) may be threaded in a bracket 200 mounted on the door panel 28 and serving as a guide for upward and downward movement of a gravity- or spring-actuated detent or keeper 202 having a laterally projecting lug 204 adapted to be accommodated in a notch 206 in the latch bar 104. The keeper has its lower end 208 extending through a guide opening 210 in the bottom 78 of the upper door panel 28 and adapted to rest on the top 80 of the lower door panel 30 when the door is fully closed as shown in Fig. 1 and until the doors are separated a slight amount, say about $\frac{1}{8}$ inch. When the operator raises the handle 88, not only is the hook 98 shifted laterally to an extent permitting it to pass through the opening 100 when the door panels are separated, but the latch bar 104 is moved to the left (Fig. 1) until said bar is free of the housing 110. At this time, the notch 206 in the latch bar 104 is in a position to receive the lug 204 of the keeper 202 upon slight separation of the door panels. When the operator raises the handle 88 he not only moves the hook 98, latch bar 104 and locking bolt 122 to open the switch 168, but, as a part of the same operation, he raises the upper door panel 28 and thus, through the chain 68 and chain rod 64, enables the lower panel 30 to gravitate downward, whereupon the notch 206 in the latch bar 104 receives the lug 204 on the keeper 202, and thus the latch bar 104 is retained in its retracted position until the door panels are again in such proximity that the top 80 of the lower panel 30 engages the bottom 208 of the keeper 202 and lifts the lug 204 sufficiently to separate the lug from the notch 206.

As the doors proceed to separate, the latch bar lug 108 passes above the top of the housing opening 190, at which position the housing obstructs such movement of the latch bar 104 as would tend to return the locking bolt 122 to switch-closing position. When the separation of the door sections has proceeded to such an extent that the latch bar lug 108 is completely free of the locking bolt 122, and until the separation of the door sections is complete, the projection 132 of the locking bolt 122 is in juxtaposition to the

upper end 62 of the anchoring member 56 or to the chain rod 64 thereabove, the spacing of the projection 132 from the part 62 and rod 64 at such times being such that accidental movement of the locking bolt 122 into engagement with such part and rod would be insufficient to bring about a closure of the switch 168 even were the wedge cam 188 absent or not functioning. It will be observed that the means just described for positively preventing closure of the switch independently of the wedge cam 188 when the doors are not latched involves a substantial improvement over the prior art, since it is dependent upon the parts 56 and 64, the removal of either or both of which would render inoperative the suspension means whereby the doors are operated together. Thus my construction for preventing closing of the switch 168 while the door is open is tamper-proof.

When the door panels 28 and 30 are fully open, stop members 212, of which one is shown in Fig. 9, fastened to the top of the lower door section 30, engage the sill 24 with a trucking plate 214 at the top of said lower section substantially flush with said sill.

When it is desired to proceed with the car, the operator closes the door. As the upper door section 28 descends, the latch lug 108 rides free as indicated in dotted lines in Fig. 7, where it is held by the detent 204, in position to descend into the notch 130 in the locking bolt 122, entering said notch as the door panels come together. Thus the latch bar 104 has no frictional contact with the housing 110 or other part during the opening and closing of the door. Shortly before the door is closed, the bottom 208 of the keeper 202 engages the top 80 of the lower panel 30 and, as the panels thereafter approach closed positions, the keeper is raised, so that the keeper lug 204 is freed of the notch 206 in the latch bar 104. This occurs substantially when the upper end of the latch lug 108 has passed below the top of the opening 190 in the housing 110, the lug 108 being then disposed substantially entirely in the locking bolt notch 130, the hook 98 has passed below the lower panel flange 80, and the projection 132 on the locking bolt 122 has passed below the upper part 62 of the anchoring member 56. The compression spring 92 then automatically moves the latch bar 104, the hook 98 and the locking bolt 122 to the right as shown in the drawings, bringing the parts into the relation shown in Fig. 5. At such time the locking lug 184 of the switch lever 118 is spaced from the adjacent wall 216 of the housing sufficiently to permit the end 182 of the locking arm 178 to pass therebetween, and it will be noted further that while the contacts 152 and 156 are allowed to engage, the wedge cam 188 on the arm 186 has prevented the contact 150 from engaging the contact 154 with the result that the switch 168 is still open. The operator now pushes a car control button (not shown). Pushing of the button closes the switch 168 (Fig. 7) and retires the retiring cam from the roller 174, enabling the spring 180 to rotate the locking arm 178 until the end 182 of said arm is disposed between the lug 184 of the switch lever 118 and the adjacent housing wall 216, said spring thereby also rotating the rock shaft 170 and with it the wedge cam arm 186, drawing the wedge cam 188 out of the way of the contact bridge 148, which is thereupon moved by the spring 146 in a manner to enable the contact 150 to engage the contact 154 and thereby close the

switch 166 so as to operate the relay 162 and hence the car motor 164 to move the car.

The safety wedge cam 188 is provided to satisfy Underwriters Laboratories requirements for States requiring such a safety feature. However, this feature may be omitted as shown in Fig. 10, wherein (except for the cam 188) the construction and operation are identical with those hereinabove set forth.

In the event the arrangement of Fig. 10 is employed, the cam roller 174 is moved by a stationary cam 176 (Fig. 2) on the car every time the elevator car approaches a floor, thereby moving the locking arm 178 to the position shown in Fig. 6. Thus the switch 166 cannot be opened unless the car is substantially at a floor. The switch 166 is in series with a switch controlled by the operator, such as the switch 168 shown in Fig. 7, enabling him to bring the car to a stop at any floor without preselecting the floor. If, after the locking arm 178 has been so shifted by the stationary cam on the car, the operator does not wish to stop the car at the adjacent floor, the stationary cam moves past the roller 174, allowing the spring 180 to return the locking arm 178 to its obstructing position as shown in Fig. 4, thereby positively preventing accidental opening of the switch 166. If, at the time the locking arm 178 is shifted to the position shown in Fig. 6, the car is brought to a stop, then the operator can raise the handle 88 to thereby retract the latch bar 104 sufficiently to withdraw the locking bolt 122 and thereby open the switch 166. Thereafter the switch 166 can be closed only provided the projection 132 on the locking bolt 122 is below the part 62 of the anchoring member 56, and the latch bar lug 108 is below the top of the opening 190 in the housing 110, at which time the door is closed. When the car is thereupon started, the stationary cam thereon moves beyond the roller 174, allowing the spring 180 again to move the locking arm 178 to its Fig. 4 position preventing opening of the switch 166.

It will be apparent from the foregoing that I have provided a fool-proof, simple and compact interlock which is entirely dependable and has all of the advantages herein set forth.

While there is shown and described herein certain specific structure embodying the invention, it will be manifest to those skilled in the art that various modifications and rearrangements of the parts may be made without departing from the spirit and scope of the invention, and that the same is not limited to the particular forms herein disclosed, except insofar as indicated by the appended claims.

I claim:

1. In an elevator or the like, a hoistway, a car in said hoistway, an electric motor for said car, a motor control switch under the control of the car operator, a biparting door comprising door sections associated with each floor of said hoistway, means connecting said sections for simultaneous movement, latch means including a movable latch member for each door, a motor control switch associated with each door and including a switch arm movable into closed position by said latch member when said latch member is moved to latching position, and a motor control circuit including said switches, said motor being operative only when both switches are closed, and means for preventing closure of the second switch when said door is open, said closure-preventing means being provided on said con-

necting means so as to be irremovable without rendering said connecting means inoperative.

2. In an elevator or the like, a hoistway, a car in said hoistway, an electric motor for said car, a motor control switch under the control of the car operator, a biparting door comprising door sections associated with each floor of said hoistway, means connecting said sections for simultaneous movement, latch means including a movable latch member for each door, a motor control switch associated with each door and including a switch arm movable into closed position by said latch member when said latch member is moved to latching position, a motor control circuit including said switches, said motor being operative only when both switches are closed, means for preventing closure of the second switch when said door is open, said closure-preventing means being provided on said connecting means so as to be irremovable without rendering said connecting means inoperative, and means for preventing opening of said second switch when said car is not at a floor.

3. In an elevator or the like, a hoistway, a car in said hoistway, an electric motor for said car, a motor control switch under the control of the car operator, a biparting door comprising door sections associated with each floor of said hoistway, means connecting said sections for simultaneous movement, latch means including a movable latch member for each door, a motor control switch associated with each door and including a switch arm movable into closed position by said latch member when said latch member is moved to latching position, a motor control circuit including said switches, said motor being operative only when both switches are closed, means for preventing closure of the second switch when said door is open, said closure-preventing means being provided on said connecting means so as to be irremovable without rendering said connecting means inoperative, and means for preventing opening of said second switch when said car is not at a floor.

4. In an elevator, a hoistway, a car in said hoistway, an electric motor for said car, push-button control means for said motor, a door at each floor of said hoistway, a motor control switch comprising a movable contact arm, a motor control circuit including said push-button control means and switch, said motor being operative only when a push-button switch and the other switch are both closed, a latch member for said door and operative upon said switch arm to open and close said other switch, means movable with said door and operative to prevent said arm from closing said other switch when said door is open, and means controlled by said car and preventing accidental closure of said other switch when said car is substantially at rest at the selected floor.

5. In an elevator, a hoistway, a car in said hoistway, an electric motor for said car, push-button control means for said motor, a door at each floor of said hoistway, a motor control switch comprising a movable contact arm, a motor control circuit including said push-button control means and switch, said motor being operative only when a push-button switch and the other switch are both closed, a latch member for said door and operative upon said switch arm to open and close said other switch, means movable

with said door and operative to prevent said arm from closing said other switch when said door is open, means controlled by said car and preventing accidental closure of said other switch when said car is substantially at rest at the selected floor, and means controlled by said car for preventing switch-opening movement of said switch arm when said car is not substantially at the selected floor.

6. In an elevator, a hoistway, a car in said hoistway, an electric motor for said car, push-button control means for said motor, a door at each floor of said hoistway, a motor control switch comprising a movable contact arm, a motor control circuit including said push-button control means and switch, said motor being operative only when a push-button switch and the other switch are both closed, a latch member for said door and operative upon said switch arm to open and close said other switch, means movable with said door and operative to prevent said arm from closing said other switch when said door is open, means controlled by said car and preventing accidental closure of said other switch when said car is substantially at rest at the selected floor, and means controlled by said car for preventing switch-opening movement of said switch arm when said car is not substantially at the selected floor, the last mentioned means being inoperative when said car is substantially at the selected floor.

7. In an elevator or the like, a hoistway, a car in said hoistway, an electric motor for said car, a motor control switch under the control of the car operator, a biparting door comprising door sections associated with each floor of said hoistway, one of said sections having a latch member, a relatively stationary switch mounted in said hoistway in association with each floor and including a movable contact member, a motor control circuit including said switches, said motor being operative only when said switches are closed, and means connecting said door sections for simultaneous movement, a connecting element substantially rigid with one of said sections and forming an essential part of said connecting means, whereby removal of said element would render said connecting means inoperative, said element having a recess disposed to receive a part carried by said arm only when said door is closed, to permit said arm to move into switch-closing position, a portion of said element adjacent said recess being disposed to obstruct movement of said arm into switch-closing position for all open positions of said sections.

8. In an elevator or the like, a hoistway, a car in said hoistway, an electric motor for said car, a motor control switch under the control of the car operator, a biparting door comprising door sections associated with each floor of said hoistway, one of said sections having a latch member, a relatively stationary switch mounted in said hoistway in association with each floor and including a movable contact member, a motor control circuit including said switches, said motor being operative only when said switches are closed, means connecting said door sections for simultaneous movement, a connecting element substantially rigid with one of said sections and forming an essential part of said connecting means, whereby removal of said element would render said connecting means inoperative, said element having a recess disposed to receive a part carried by said arm only when said door is closed, to permit said arm to move into switch-

closing position, a portion of said element adjacent said recess being disposed to obstruct movement of said arm into switch-closing position for all open positions of said sections, and means yieldably urging said contact arm into switch-closing position when said door is closed.

9. In an elevator or the like, a hoistway, a car in said hoistway, an electric motor for said car, a motor control switch under the control of the car operator, a biparting door comprising door sections associated with each floor of said hoistway, one of said sections having a latch member, a relatively stationary switch mounted in said hoistway in association with each floor and including a movable contact member, a motor control circuit including said switches, said motor being operative only when said switches are closed, means connecting said door sections for simultaneous movement, a connecting element substantially rigid with one of said sections and forming an essential part of said connecting means, whereby removal of said element would render said connecting means inoperative, said element having a recess disposed to receive a part carried by said arm only when said door is closed, to permit said arm to move into switch-closing position, a portion of said element adjacent said recess being disposed to obstruct movement of said arm into switch-closing position for all open positions of said sections, and means including a latch member for moving said contact arm into and out of switch-closing position when said door is closed while said car is substantially at rest at the floor associated with said door.

10. In an elevator or the like, a hoistway, a car in said hoistway, an electric motor for said car, a motor control switch under the control of the car operator, a biparting door comprising door sections associated with each floor of said hoistway, one of said sections having a latch member, a relatively stationary switch mounted in said hoistway in association with each floor and including a movable contact member, a motor control circuit including said switches, said motor being operative only when said switches are closed, means connecting said door sections for simultaneous movement, a connecting element substantially rigid with one of said sections and forming an essential part of said connecting means, whereby removal of said element would render said connecting means inoperative, said element having a recess disposed to receive a part carried by said arm only when said door is closed, to permit said arm to move into switch-closing position, a portion of said element adjacent said recess being disposed to obstruct movement of said arm into switch-closing position for all open positions of said sections, and means including a latch member for moving said contact arm into and out of switch-closing position when said door is closed while said car is substantially at rest at the floor associated with said door, and means preventing unlatching movement of said latch member when said car is not substantially at rest.

11. In an elevator or the like, a hoistway, a car in said hoistway, an electric motor for said car, a motor control switch under the control of the car operator, a biparting door comprising door sections associated with each floor of said hoistway, one of said sections having a latch member, a relatively stationary switch mounted in said hoistway in association with each floor and including a movable contact member, a motor control circuit including said switches, said motor being operative only when said switches are

closed, means connecting said door sections for simultaneous movement, a connecting element substantially rigid with one of said sections and forming an essential part of said connecting means, whereby removal of said element would render said connecting means inoperative, said element having a recess disposed to receive a part carried by said arm only when said door is closed, to permit said arm to move into switch-closing position, a portion of said element adjacent said recess being disposed to obstruct movement of said arm into switch-closing position for all open positions of said sections, and means preventing switch-opening movement of said contact arm when said car is not substantially at rest.

12. In an elevator, a hoistway, a car in said hoistway, an electric motor for said car, push-button control means for said motor, a door at each floor of said hoistway, a motor control switch comprising a movable contact arm and a biased switch contact, a motor control circuit including said push-button control means and switch, said motor being operative only when a push-button switch and the other switch are both closed, a latch member for said door and operative upon said switch arm to open and close said other switch, means obstructing open-switch movement of said contact arm while said car is en route to but substantially remote from the selected floor, and means controlled by said car and simultaneously opening said other switch and moving said obstructing means to non-obstructing position when said car substantially reaches the selected floor, said controlled means including a member forced by said car to move said contact to open-switch position in opposition to the bias thereon.

13. In an elevator, a hoistway, a car in said hoistway, an electric motor for said car, push-button control means for said motor, a door at each floor of said hoistway, a motor control switch comprising a movable contact arm and a biased switch contact, a motor control circuit including said push-button means and switch, said motor being operative only when a push-button switch and the other switch are both closed, a latch member for said door and operative upon said switch arm to open and close said other switch, means obstructing open-switch movement of said contact arm while said car is en route to but substantially remote from the selected floor, means controlled by said car and simultaneously opening said other switch and moving said obstructing means to non-obstructing position when said car substantially reaches the selected floor, said controlled means including a member forced by said car to move said contact to open-switch position in opposition to the bias thereon, and means movable with said door to prevent said arm from closing said switch when said door is open.

14. In an elevator installation including a hoistway having a plurality of landings with each of which the panels of a vertically sliding biparting hoistway door and a switch are associated, a car having a retiring cam and disposed in said hoistway, a motor for said car, a push-button control for said motor, a motor control circuit including said switch and push-button control, said motor being operative only when said switch and a push-button switch are closed, the first switch having a movable arm carrying a contact bridge, a spring pressing said bridge, a latch bar

for said door and connected with said switch arm when said door is closed and being movable to latching position when said car is at rest at the associated landing, a member movably mounted at each landing and yieldably held in a position locking said switch arm in closed-switch position when said door is latched, said member being movable from such position by the retiring cam to unlock said switch arm and against the resistance of said spring to lock said bridge in open-switch position until said cam is retired while said switch arm is in closed-switch position, said latch bar being retractable, when said switch arm is unlocked, to unlatch said door and move said switch arm to open-switch position, means for maintaining said latch bar in retracted position while said door is open, means connecting said door sections for simultaneous movement, and means including said connecting means for locking said switch arm in open-switch position while said door is open.

15. In an elevator installation including a hoistway having a plurality of landings with each of which the panels of a vertically sliding biparting hoistway door and a switch are associated, a car having a retiring cam and disposed in said hoistway, a motor for said car, a push-button control for said motor, a motor control circuit including said switch and push-button control, said motor being operative only when said switch and a push-button switch are closed, the first switch having a movable arm and a spring-pressed contact, a latch bar for said door and connected with said switch arm when said door is closed and being movable to latching position when said car is at rest at the associated landing, a member movably mounted at each landing and yieldably held in a position locking said switch arm in closed-switch position when said door is latched, said member being movable from such position by the retiring cam to unlock said switch arm and against the resistance of said spring to lock said contact in open-switch position until said cam is retired while said switch arm is in closed-switch position, said latch bar being retractable, when said switch arm is unlocked, to unlatch said door and move said switch arm to open-switch position, means for maintaining said latch bar in retracted position while said door is open, means connecting said door sections for simultaneous movement, and means including said connecting means for locking said switch arm in open-switch position while said door is open.

16. In an elevator, a hoistway, a car in said hoistway, an electric motor for said car, push-button control means for said motor, a door at each floor of said hoistway, a motor control switch comprising a movable contact arm, a motor control circuit including said push-button control means and switch, said motor being operative only when a push-button switch and the other switch are both closed, a latch member for said door and operative upon said switch arm to open and close said other switch, means movable with said door and operative to prevent said arm from closing said other switch when said door is open, means controlled by said car and preventing accidental closure of said other switch when said car is substantially at rest at the selected floor, and means for moving the last mentioned means to inoperative position before said car starts.
